TRANSFORMER CLAMP

Hirsch Epstein, Chicago, Ill., assignor of one-half
to Louis R. Duman, Chicago, Ill.

Application February 24, 1947, Serial No. 730,630

1 Claim. (Cl. 175—356)

1

This application is a continuation in part of my pending application Serial No. 567,542, filed December 11, 1944, which is now abandoned.

The present invention relates to transformers or reactors and more particularly such as are used in connection with alternating current hot cathode fluorescent lighting devices.

It is one of the objects of the present invention to provide a reactor or transformer which will operate as noiselessly as possible.

The core of the transformers of the above mentioned type generally consists of a series of thin laminations, of substantially L shape, laid to form a rectangular core. I have found that the end laminations are primarily responsible for the transformer noises. Various means have been suggested heretofore for clamping the laminations together to reduce the permissible vibration and thus reduce the noise. Insofar as I am aware the various means provided for noise reduction have been either costly or unsatisfactory. I have discovered that a simple soft iron clamp, of a generally C shape, positioned to embrace and hold the opposite sides of the core at the free or vibrating end of the outermost laminations can be used to prevent vibration of the lamination and thus substantially reduce or entirely eliminate transformer noises.

It is an object of the present invention to provide a simple and inexpensive clamping arrangement for holding the ends of the transformer laminations together and thus reduce the noise making tendency of the transformer. It is a further object of the present invention to provide a clamp which is particularly adapted to hold together the adjacent ends of the two laminations constituting the outermost laminations of the core and thus to prevent those ends from vibrating. It is a still further object of the present invention to provide an improved means for assembling and fabricating the noise reducing clamp at the end of the transformer.

The attainment of the above and further objects of the present invention will be apparent from the following specification taken in conjunction with the accompanying drawing forming a part thereof.

In the drawing:

Figure 1 is a top view of a transformer, partly broken away, illustrating the present invention;

Figure 2 is a fragmentary sectional view taken along the line 2—2 of Figure 1;

Figure 3 is an enlarged fragmentary sectional view taken along the line 3—3 of Figure 1 and illustrating also the condition of the clamp as it is being die formed;

2

Figure 4 is an elevational view of the dies in which the clamp is being pressed into position;

Figure 5 is a plan view of the structure of Figure 4 and showing the transformer in position;

Figures 6 and 7 are views corresponding to Figures 4 and 5 and showing an alternate die arrangement;

Figure 8 is a view corresponding to the end of Figure 1 and showing a transformer with a clamp fabricated in accordance with the process of Figures 6 and 7;

Figure 9 is a sectional view taken along the line 9—9 of Figure 8; and

Figure 10 is a fragmentary view of the end of a transformer showing another clamping arrangement.

Reference may now be had more particularly to the drawing wherein like reference numerals designate like parts throughout.

In Figure 1 I have shown my invention as applied to a standard type transformer such as is used in connection with fluorescent lighting devices. The transformer 1 comprises a plurality of individually wound coils 2, which may be of identical or different characteristics. Each coil is wound on a cardboard or other stiff paper spool 6. A laminated iron core structure 7 is assembled through the spools 6 of the coils. This core structure comprises a series of identical L-shaped silicon steel laminations as is usual in the art. Each lamination includes a long leg 12 which extends longitudinally of the finished transformer through a set of coils, and a short leg 13 which extends laterally of the transformer. The laminations are assembled to form a rectangular core in which the long leg 12 of each lamination extends the full length of the core, whereas the short leg 13 terminates at a line 14. The lateral leg of each lamination is of a length less than the width of the transformer. The laminations are laid in layers so that the meeting edges 14 of the two laminations of the same layer are on diagonally opposite sides of the core and so arranged that in adjacent layers the meeting edges 14 are on opposite diagonals of the rectangular core. Each lamination consists of a silicon steel strip approximately $\frac{1}{40}$ of an inch thick. After the core has been assembled it is locked in place by longitudinally extending wooden wedges 18—19 which are tapered at one end, as indicated at 20, and are forced through the coils between the top lamination and the tubes 6. The wedges thus hold the laminations tightly clamped together along the longitudinal sides of the transformer.

It is to be noted that the free lateral ends

of the lateral legs 13 of the two top and the two bottom laminations are not locked in place by the wedges 19-19. The ends of those legs 13 will therefore tend to vibrate and produce transformer noises unless means is provided to prevent this. In order to prevent vibration of the lateral ends of the upper and lower outermost laminations I provide at each end of the transformer a C-shaped or channel-shaped clamp 25 of soft steel or iron which is dead, that is, substantially devoid of springiness. The bight portion 26 of each clamp 25 is spaced from the core. The arms 27-28 bear against opposite lateral faces of the transformer and may, optionally, be spaced from those faces by a sheet of paper to prevent the establishment of a magnetic path between the uppermost and the lowermost lamination. The sheet of paper may be omitted because generally there is enough of a film of oxide on the lamination of the magnetic core and on the surfaces of the arms 27 and 28 of the clamp to prevent any serious eddy current action developing. The C-shaped clamp 25 is placed on the transformer and then the arms 27-28 are firmly pressed towards one another as in a pneumatic or hand press. This holds the C-clamp in position. Thereafter the end of the transformer may be wound with a paper strip in the usual manner to provide for the terminals of the wires of the transformer coils. The transformer is then coated with an insulating varnish and placed in a container and completely encased by an insulating compound, such as tar, within the container, as is usual in the art, and shown in my application above referred to.

In Figures 4 and 5 I have shown a die arrangement such as is used for securing the clamp 25 in place. This clamping arrangement includes a pair of relatively movable dies 39 and 40 of a manual or pneumatic press of which both dies may be movable towards one another or one may be stationary. The die 40 includes a die head 41 having a pair of spaced apart ears 42-42 between which is pivotally mounted a die block 43 as by a pivot pin 44. The die block 43 is free to turn through a limited angle about the longitudinal axis of the pin 44. Below the ears 42 the die head 41 has secured thereto a gauge plate 46 which is adjustably secured to the die head at any desired distance below the ears 42. The gauge plate has at the rear thereof an upstanding gauge stop pin 47. The working surface of the die block 43 is concave, as indicated at 48, being curved on such a radius that the depth of the concavity, for the width of the die block, is approximately half the thickness of the metal of the clamp 25. The die 39 has a die block 50 in line with the die block 43 and having a concave working face 51 similar to the concave working face 48.

An explanation will now be given of the manner of securing the clamp 25 in place. The opposite arms of the clamp 25 are initially spaced apart an amount sufficient to permit them to embrace a stack of laminations between the wedges 18-19. At this time the thickness of the stack of laminations is somewhat greater than will be their ultimate thickness after compression. Thereafter the end of the stack of laminations is placed on the gauge plate 46 and in engagement with the gauge stop pin 47. This accurately positions the stack of laminations with respect to the dies 43-50. The two die heads 39-40 are then brought together under

great pressure. The concave surfaces 48-51 engage the opposite arms 27-28 of the clamp 25 and force them together, deforming the metal of the clamp beyond its elastic limit. The fact that the die block 43 is pivoted assures a proper equalization of force at the opposite edges of each die block. The pressure of the dies on the clamp not only deforms the clamp but also compresses the stack of laminations so that upon removal from the die the stack of laminations are compressed by and exert an outward pressure against the arms 27-28 of the clamp.

Figure 3 shows an enlarged view of the face 48 of the die block 43. In this instance the block as seen in Figure 3 is $\frac{5}{8}$ inch wide and has at each end thereof a flat surface 60 which is approximately $\frac{1}{16}$ inch wide. The depth of the concave surface is approximately half of the thickness of the metal of the arm 27 of the clamp 25. The die block 43 extends across the line 14 which is the gap between the two meeting laminations at the same level. The clamp 25 exerts its maximum pressure against the stack of laminations on each surface thereof along two areas of pressure, indicated at 65, one of which areas is immediately over the gap 14 between the laminations and the other of which is an equal distance on the opposite side of the center of the transformer. The clamp therefore holds the edges 66 and 67 against vibration. It is at those edges where the maximum vibration would otherwise take place and where the maximum noise would be produced.

In Figures 6 and 7 I have shown a structure somewhat different from that of Figures 5 and 6, for accomplishing similar results. In this case the relatively movable die heads are indicated at 69 and 70. A die block 71 is rigid with respect to the die head 69, and a die block 72 is pivoted between a pair of ears 73 in the die head 70 as by a pivot pin 74. A pair of plunger pins 75-75 are rigidly mounted in the die block 71 and a similar pair of pins 76-76 are rigidly mounted in the die block 72 which is pivoted to the die head 70. Each of the pins 75 terminates in a conical point. These points deform the arms 27-28 of the clamp 25 and produce in each arm a pair of protuberances which are in intimate pressure engagement with the outermost laminations. The points of the pins 75 are conical or spherical. There is sufficient give in the metal of the clamp so that the protuberances on the inner surfaces of the arms 27-28, which engage the stack of laminations, are of a generally spherical shape and of a comparatively large radius. The protuberances overlie the transformer on both sides of the line 14, and clamp the stack of laminations together. In view of the fact that the protuberances overlie the line 14 on one side of the longitudinal center line of the transformer and there are similar protuberances similarly located on the opposite side of the longitudinal center line of the clamp, the outer laminations of the core are thus positively kept from vibrating.

The dies of either Figures 4 and 5 or Figures 6 and 7 may be used in connection with a somewhat overheight clamp to advantage. This is illustrated in Figure 10. In Figure 10 there is shown in dotted lines an overheight clamp which is to be deformed to hold a stack of laminations together. In this instance the non-pivoted die 50 includes a backing support 85 that backs the clamp for half the height of the clamp. The movable die block 43 includes a stop 86 that

engages the edge 87 of the clamp and holds it against movement inwardly towards the transformer coils. As the die 43' moves towards the die 50' and forces the end 27 of the arm of the clamp towards the stack of laminations it causes the metal at 88 to bulge away from the core and produce a bulge 89. The metal along the curved portion 90 is deformed in such a manner that any straining tendency is in a direction such as to tend to cause the metal at 81 to move towards the transformer core rather than away from it, so that the bulge 89 constitutes material tending constantly to press the arm 21 towards the stack of laminations. The clamp of Figure 10 may therefore be made of spring metal instead of dead metal if desired.

In compliance with the requirements of the patent statutes I have here shown and described a few preferred embodiments of my invention. It is, however, to be understood that the invention is not limited to the precise constructions here shown, the same being merely illustrative of the principles of the invention. What I consider new and desire to secure by Letters Patent is:

Alternating current apparatus comprising a 25 laminated core, and soft iron clamping straps extending across the laminations and embracing the lateral sides of the core from an outermost lamination on one side of the stack to the outermost lamination on the opposite side of the stack 30 and exerting pressure against the stack for clamping the laminations of the stack together, each clamping strap having a pair of arms having concentrated pressure areas adjacent opposite edges thereof and each clamp having an intermediate 35

portion adjoining the said arms thereof, there being substantially a U-shaped bend in the metal of the clamping strap at the juncture between the intermediate portion and one of the arms and with the open side of the U facing the space between the arms.
